MARINE FLARE

Frank Lawson Ogle, Liverpool, England, assignor
to Imperial Chemical Industries Limited, a cor-
poration of Great Britain

Application October 7, 1943, Serial No. 505,416
In Great Britain October 7, 1942

7 Claims. (Cl. 9—8.3)

This invention relates to marine flares.

It is an object of this invention to produce a marine flare which can be manufactured with a high degree of safety, and which will be actuated by placing the same in water.

It is another object of this invention to produce a marine flare which when placed in water will have a delayed action.

It is a further object of this invention to produce a marine flare in which the flare-producing materials are sealed with water-soluble plugs which are automatically removed by contact with water.

Other objects of the invention will be evident from the following description.

The accompanying illustration, which will be hereafter referred to in detail, is a diagrammatic vertical sectional view of a flare constructed in accordance with the invention.

According to the present invention, a marine flare comprises a closed metal container adapted to float in water, which container is divided into two compartments capable of being put into communication through a passage or passages normally closed by a solid combustible or easily fusible body, the one compartment containing a light hydrocarbon such as paraffin, benzene or petrol, and the second an alkali metal such as sodium, the said second compartment being adapted to admit water when the device is thrown into water, and having a portion above the water level with a relatively weak wall capable of being disrupted as a result of the reaction of the alkali metal with the water, thereby opening the compartment to the atmosphere. Advantageously the relatively weak wall is a metal closure soldered on by a low-melting solder.

When such a device is thrown into water, water enters the compartment containing the alkali metal, whereby sufficient heat is generated both to disrupt the relatively weak portion of the compartment and to cause the plug or seal in the passage or passages joining the two compartments to burn or fuse, and thus to admit the hydrocarbon to the sodium-containing compartment and cause it to catch fire.

If desired the metal container may also contain other compartments containing smoke-producing materials or the materials to produce coloured lights. Such other compartments may also be adapted to contain large quantities of a cheaper, more difficultly combustible or heavier oil which will float on water, and to release the oil when the flare is thrown into the water. On throwing the device into water, the oil will be

dispersed on the water and will be set alight by the fire generated by the sodium and the light hydrocarbon.

To retain such oil in the container before it is thrown into the water and to prevent the prior decomposition of the sodium, the appropriate compartments may be sealed with water-soluble plugs, or they may each have a perforated wall over which a cap is normally fitted and which can be removed before the device is thrown or projected into the water. Alternatively the alkali metal-containing compartment may be sealed and the container punctured before it is thrown into the water at a place which will be 15 below the water level. The use of a water-soluble plug has the advantage that there is a time lag between throwing the device into water and the onset of the reaction of the water with the alkali metal. This allows the lifeboat or other vessel 20 from which the flare is thrown to get clear of the flare before it lights up.

In one form of the invention the metal container has one central cylindrical compartment with an annular compartment around it, the wall 25 common to the two having perforations or slots sealed by, for example, tin foil or a low-melting solder. The device is weighted so that when thrown into water it will float with one end of the central compartment below the water and the other above it. The outer compartment has a closeable opening through which it can be filled with petrol, paraffin or the like. The inner compartment has at the lower end a perforated bottom whose perforations are sealed by a water- 30 soluble plug, and at the upper end a plate carrying a removable lid through which the alkali metal can be introduced and in which is a small orifice through which gas can escape slowly. Both the sealed perforated bottom and the plate 35 at the top are rendered air-tight and watertight by a very light gauge plate soldered on, each of which is in turn protected against mechanical damage by a lid of heavier gauge held on by friction, and provided with a cutter by 40 which the light gauge plate can be cut off when the flare is to be used. Instead of having a perforated lid at the ends which are protected by air-tight lids to be cut away, single closures may be provided at each end sealed on by low melting solder, and the necessary openings made before 45 use by puncturing.

The outer compartment is filled with paraffin, petrol or the like, and a mass of alkali metal, e. g., sodium, is put into the inner compartment. 50 The closures are then put on the latter compart-

ment and the device can then be stored indefinitely.

When it is desired to use the flare the outer loose lid over each end of the inner compartment is removed, and the thin gauge seals cut off by the cutters. The device is then thrown into the water. Water enters the inner compartment through the perforations below the water level while the gas displaced by it escapes by the small orifice at the top and the water reacts with the sodium. Gas is generated more rapidly than it can escape through the orifice in the upper lid, and this and the heat generated by the reaction causes the lid to be blown off and the sodium to catch fire. The tin foil is thus melted, whereby the petrol or other light hydrocarbon in the outer compartment is admitted to the flaming sodium and itself takes fire.

Referring to the above-mentioned illustration, the central cylindrical compartment 1 has an annular compartment 2 surrounding it for its whole length except for a short portion at either end allowing caps 3 and 12 to be fitted over the ends of the compartment 1. The one end of compartment 1 closed by cap 3 has a perforated bottom 5 sealed by a plug 6 of water-soluble material and outside this is soldered on a plate 14 of light gauge material. The other end of compartment 1 is closed by a sheet of light gauge metal 4, which is soldered on, and has within it a closure 7, carrying a lever lid 13. Lid 13 has a small opening 8. A loose cover 12 over the cap 4 is fitted with a small cutter (not shown) by which the thin metal sheet 4 can be opened when the apparatus is used. Cap 3 is similarly provided with a cutter for removing the plate 14. The wall of compartment 1 has a number of slots 9 (one of which is shown) sealed by tin foil soldered on, through which slots the inner compartment 1 communicates with the outer compartment 2 when the foil is removed. The latter compartment has ballast 10 fixed to the same end of the flare as perforated bottom 5 of compartment 1 to ensure that when thrown into water the device will float with the bottom 5 in the water and opening 8 above it. The container 2 can be filled with petrol, paraffin, or the like by means of a screw cap 11.

When the apparatus is prepared for use, the water-soluble plug 6 is applied, compartment 1 is charged with sodium or other alkali metal through lid 12, and afterwards plates 4 and 7 are soldered on. Compartment 2 is filled with petrol or its equivalent through screw cap 11 and cap 3 and cover 12 are put on. Caps 3 and 12 protect the metal sheets 4 and 14 from damage and provide the cutting instrument for removing them when desired.

To use the flare, caps 3 and 12 are used to cut off the metal sheets 4 and 14 and are then removed, and the device is thrown into water. It automatically floats with the perforated bottom 5 of the compartment 1 below water, so that after a short interval water dissolves away plug 6 and enters the compartment 1, air being displaced through the opening 8. The water will thus react with the sodium and generate hydrogen, so that lid 13 is blown off, and the remaining sodium catches fire. The tin foil sealing slots 9 is thus melted so that the petrol or its equivalent is admitted to the flaming sodium and itself catches fire. Depending on the relative strengths of the lid 13 and the seals on slots 9 either may be disrupted first, and in some cases it may be preferable for the seals on slots 9 to be broken first,

partly by the heat, and partly by the pressure generated in compartment 1.

I claim:

1. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, partitioning means between said compartments, said partitioning means composed of a material which will be removed as a result of the reaction of water and alkali metal to form a passageway between said compartments, and means actuated by the pressure generated by said reaction to open said alkali metal-containing compartment to the atmosphere.

2. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, a water-soluble sealing means over said opening, partitioning means between said compartments, said partitioning means composed of a material which will be removed as a result of the reaction of water and alkali metal to form a passageway between said compartments, and means actuated by the pressure generated by said reaction to open said alkali metal-containing compartment to the atmosphere.

3. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, said alkali metal-containing compartment having a vent to the atmosphere above the surface of the water, partitioning means between said compartments, said partitioning means composed of a material which will be removed as a result of the reaction of water and alkali metal to form a passageway between said compartments, and means actuated by the pressure generated by said reaction to open said alkali metal-containing compartment to the atmosphere.

4. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, said alkali metal-containing compartment having a vent to the atmosphere above the surface of the water, a water-soluble sealing means over the said opening, partitioning means between said compartments, said partitioning means composed of a material which will be removed as a result of the reaction of water and alkali metal to form a passageway between said compartments, and means actuated by the pressure generated by said reaction to open said alkali metal-containing compartment to the atmosphere.

5. A marine flare comprising a container which will float in water in a given position, said con-

tainer having a compartment containing a light hydrocarbon and a compartment containing an alkali metal, said alkali metal-containing compartment having an opening therein below the water level to permit flow of water to said compartment when said container is afloat, a soldered metal foil between said compartments, and means actuated by the pressure generated by said reaction to open said alkali metal-containing compartment to the atmosphere.

6. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, said alkali metal-containing compartment having a vent to the atmosphere from said compartment above the surface of the water, a soldered metal

foil between said compartments, and means actuated by the pressure generated by said reaction to open said alkali metal-containing compartment to the atmosphere.

5 7. A marine flare comprising a container which will float in water in a given position, said container having a compartment containing a light hydrocarbon and a compartment containing an alkali metal, said alkali metal-containing compartment having an opening therein below the water level to permit flow of water to said compartment when said container is afloat, said alkali metal-containing compartment having a vent to the atmosphere from said compartment 15 above the surface of the water, a water-soluble sealing means over the said opening, a soldered metal foil between said compartments, and means actuated by the pressure generated by said reaction to open said alkali metal-containing compartment to the atmosphere.
